UNITED STATES PATENT OFFICE.

GEORGE H. CANDLER, OF BRIDGEPORT, CONNECTICUT.

DESIGN FOR A HAT-PIN.

49,138.

Specification for Design.

Patented June 6, 1916.

Application filed March 24, 1916. Serial No. 86,518. Term of patent 3½ years.

To all whom it may concern:

Be it known that I, GEORGE H. CANDLER, a citizen of the United States, residing at the city of Bridgeport, in the county of Fairfield and State of Connecticut, have invented a new, original, and ornamental Design for a Hat-Pin, of which the following is a specification, reference being had to the accompanying drawing, forming part thereof.

Figure 1 is a side elevation of a hat pin showing my new design, and Fig. 2 is an end elevation.

I claim:

The ornamental design for a hat pin as shown.

GEORGE H. CANDLER.

Witnesses:

F. W. SMITH, Jr.,
M. T. LONGDEN.
